UNITED STATES PATENT OFFICE.

CHARLES A. HUSSEY, OF NEW YORK, N. Y.

ELECTRIC TIME-INDICATING SYSTEM.

SPECIFICATION forming part of Letters Patent No. 350,432, dated October 5, 1886.

Application filed June 18, 1886. Serial No. 205,564. (No model.)

To all whom it may concern:

Be it known that I, CHARLES A. HUSSEY, of New York, in the county and State of New York, have invented a certain new and useful Improvement in Electric Time-Indicating Systems, of which the following is a specification.

I will describe an electric time-indicating system embodying my improvement, and then point out the various novel features in claims.

10 The accompanying drawing is a diagram illustrating my improvement.

All the parts which are located in the office where the system is controlled are surrounded by a line, adjacent to which I have marked the word "Office."

15 A designates the sweep second arbor in a primary mechanical clock or regulator. This clock or regulator may be of any suitable kind and operated by a weight or spring. The 20 shaft A, it must be understood makes one complete rotation during each minute. On the shaft A is affixed a wheel, A', having a notch, a', in its periphery. Adjacent to the wheel A' a wheel, A², is arranged in the primary 25 clock or regulator. As shown, the wheel A² is journaled loosely in a swinging arm, A³, which is pivotally connected to a rod, A⁴, located in the primary clock or regulator. The wheel A² rests upon the periphery of the 30 wheel A'. Whenever the notch a' in the periphery of the wheel A' comes opposite the wheel A², the latter drops into it. The arm A³ of course descends with the wheel A² when the latter drops into the notch.

35 A⁵ designates a rod in the primary clock or regulator, which has at the lower end an offset or shoulder, a, extending under the swinging arm A³. As shown, the arm A³ has a projection, a², opposite the offset or shoulder a of the rod A⁵. When the swinging arm A³ descends on the dropping of the wheel A² into the notch a' of the wheel A', the projection a² makes contact with the offset or shoulder a of the swinging arm A³. The rods A⁴ A⁵ and 40 the swinging arm A³ are to be made of metal. The other parts which I have mentioned may or may not be of metal. The rods A⁴ A⁵ are to be insulated from each other. This may be done by supporting them in a frame of insulating material, A⁶, or by interposing pieces of insulating material between them and the frame if the latter is not made of insulating

material. The rod A⁴ has connected to it a wire, A⁷, which extends to one pole of an electric battery, A⁸. From the other pole of the 55 battery A⁸ a wire, A⁹, extends. A wire, A¹⁰, extends from the rod A⁵. Whenever the swinging arm A³ descends in the manner which I have explained, and its projection a² makes contact with offset or shoulder a of the rod A⁵, 60 the wires A¹⁰ and A⁷ are in electrical communication. This electrical communication will be only momentary, owing to the fact that the notch a' of the wheel A' is of very slight extent. The notch is preferably so short in the direction 65 of the periphery of the wheel A' that the contact of the projection a² of the swinging arm A³ with the offset or shoulder a of the rod A⁵ will exist only for two seconds during each rotation of the sweep second-shaft A. The wire A¹⁰ 70 is connected to a binding-post, A¹¹, with which one end of the wire of an electro-magnet, A¹², is connected. The wire A⁹ is connected to a binding-post, A¹³, with which the other end of the wire of the electro-magnet A¹² is connected. 75

It will be understood, in view of the foregoing explanation, that whenever the swinging-arm A³ is allowed to drop so that its projection a² will make contact with the offset or shoulder 80 a of the rod A⁵, the electro-magnet A¹² will be momentarily energized from the battery A⁸. The electro-magnet A¹² has combined with it a swinging armature, A¹⁵. A spring, a³, tends to pull the armature away from the electro-magnet. The armature is attracted toward the poles of the electro-magnet whenever the latter is energized. The armature A¹⁵ vibrates between two metal contact-pieces, a⁴ a⁵, shown as consisting of screws in order to be 85 adjustable. Normally the armature will be held against the contact-piece a⁴ by the spring a³. When the electro-magnet is energized, the armature will be vibrated over against the contact-piece a⁵ momentarily. 90

B designates an electro-magnet having combined with it an armature, B², impelled in one direction by a spring, d, and moved in the other direction by the attractive force of the electro-magnet B. The armature B² vibrates 100 between two metal contact-pieces, (shown as consisting of adjustable screws,) b⁴ b⁵. Normally the armature B² is held against the contact-piece b⁴. When attracted by the electro-

magnet B, it is swung against the contact-piece b^5 .

D designates a main battery for sending currents of electricity over line-wires C' C² C³. 5 The line-wires C' C² extend from the armatures A¹⁵ B² of the electro-magnets A¹² B. The line-wire C³ extends from one pole of the battery D. A wire, D', extends from one pole of the battery D to a binding-post, d', and the latter is connected by a wire, D², with the contact-piece b^5 . A wire, D³, extends from the binding post d' to a binding-post, d⁴, which is connected by a wire, D⁴, to the contact-piece a^5 . It will be seen that as the armatures A¹⁵ 15 B² are normally separated from the contact-pieces a^5 b^5 no current passes from the battery D ordinarily. Whenever the electro-magnet A¹² is energized, so that it shifts its armature A¹⁵ against the contact-piece a^5 , an electric circuit will be completed from the battery D in one direction along the wire D' to the wire D³, thence along the wire D⁴ to the armature A¹⁵, and thence along the line-wire C', and in the other direction along the line-wire C³. If the 20 electro-magnet B is energized, its armature B² will be shifted over to the contact-piece b^5 , whereupon an electric circuit will be completed from the battery D along the wire D' to the wire D², along the latter to the armature B², and from said armature to the line-wire C³, and in the other direction along the line-wire C³.

I will here remark, in order to conduce to a clear understanding of my improvement, 35 that an electric current is caused by energizing the electro-magnet A¹² to flow over the line-wires C' C³ to cause the electric or secondary clocks which I employ to record hours and minutes, and that the electric current is caused 40 by energizing the electro-magnet B to flow from the battery D over the line-wires C² C³ for the purpose of causing other parts of the electric or secondary clocks to record days, in order that they may serve as calendars.

45 I will now describe the mechanism whereby the operation of the electro-magnet B is controlled. A wire, B³, extends from the wire A⁹ to a binding-post, which is connected with one end of the wire of the electro-magnet B. 50 The other end of the wire of the electro-magnet B is connected to a binding-post with which a wire, B⁴, is also connected. The wire B⁴ is connected to a rod, B⁵, in the primary mechanical clock or regulator. This rod B⁵ is to be 55 made of metal, and has at the lower end an offset or shoulder, b⁶.

B⁶ is a swinging arm, made of metal, having a projection, b⁷, opposite the offset or shoulder b⁶, of the rod B⁵. The swinging arm B⁶ has 60 journals supported by bearings consisting of screws or pins b⁸, fitted in metal rods B⁷ B⁸, arranged in the primary clock or regulator. The rod B⁸ is connected by a wire, B⁹, with the rod A⁴, and hence is in electric communication with the wire A⁷, which leads to one pole of the battery A⁸. The rods B⁵ B⁸ are insulated from each other and from the rods A⁴

A⁵. Whenever the swinging arm B⁶ is allowed to descend, so that its projection b⁷ will make contact with the offset or shoulder b⁶ of the 70 rod B⁵, an electric circuit will be completed from the battery A⁸, along the wire A⁷ to the wire B⁹, thence through the rod B⁸ to the swinging arm B⁶, thence over the latter to the rod B⁵, and thence along the wire B⁴ to one 75 end of the wire of the electro-magnet B. An electric current will then flow from the battery A⁸ to the wire of the electro-magnet B, because the other end of the wire of this electro-magnet is always connected to the battery A⁸ 80 through the wire A⁹. When the electro-magnet B is thus energized, its armature B² will be shifted over to the contact-piece b^5 , and an electric current will then pass from the battery D over the line-wires C² C³. 85

I will now describe the manner in which the swinging arm B⁶ is operated. B¹⁰ is a rod supported in the frame of the primary clock or regulator. Under it is arranged a rotary shaft, B¹¹, on which is affixed a wheel, B¹², having a 90 cam-surface, b⁹, on one side. The lower end of the rod B¹⁰ is provided with an offset, b¹⁰, that projects into the path of the cam surface b⁹ of the wheel B¹², and is adapted to extend under a projection, b¹¹, with which the swinging arm B⁶ is provided. The lower portion of the rod B¹⁰ is resilient. When the cam-surface b⁹ of the wheel B¹² comes opposite the rod B¹⁰, the latter will be sprung or moved aside. Its offset b¹⁰ will then be moved from 100 under the swinging arm B⁶, and the latter will descend so that its projection b⁷ will make contact with the offset b⁶ of the rod B⁵. As soon as the cam-surface b⁹ has passed by the rod B¹⁰, the latter will be ready to assume its original 105 position and support the swinging arm B⁶ again. It cannot, however, assume its normal position until the swinging arm has been raised to its normal position. The swinging arm B⁶ will be raised to its normal position by a cam 110 or eccentric, B¹³, on the sweep second-shaft A. The shaft A rotates rapidly, the swinging arm B⁶ will only be left in contact with the rod B⁵ momentarily. The shaft B¹¹ is provided 115 with a wheel, B¹⁴, which has twenty-four teeth. On the sweep second-shaft A a tubular minute-hand shaft, B¹⁵, is arranged. This minute-hand shaft makes a rotation once every hour, and is provided with a wheel, B¹⁶, having a single tooth that engages once in each rotation with the wheel B¹⁴ and moves the latter 120 a short distance. A spring-actuated tooth, B¹⁷, which engages with the wheel B¹⁴, insures the latter being moved a distance equal to the distance between two adjacent teeth each time 125 the wheel B¹⁶ engages with it. It also causes the movements of the wheel B¹⁴ to be made quickly each time it moves. The wheel B¹⁶ starts each movement of the wheel B¹⁴, and the spring-actuated tooth B¹⁷ completes the movement 130 quickly. This spring-actuated tooth B¹⁷ also prevents the wheel B¹⁴ from moving improperly. It will be understood from the description I have given that the wheel B¹⁴, the

135

shaft B^{11} , and the cam-wheel B^{12} , rotate once each twenty-four hours, or, in other words, once a day. The circuit is therefore closed to the electro-magnet B but once a day.

5 E designates the electric clocks or secondary clocks of the time-telegraph. They are arranged in multiple-arc circuit. Each has a shaft, e , which is provided with a wheel, e' , having sixty teeth. This wheel e has combined with it a pawl-lever, e^2 , which has affixed to it an armature, e^3 , for an electro magnet, e^4 . The shaft e is a minute-shaft. In other words, it makes a complete rotation once every hour. The minute-hand of the clock is affixed to this shaft. Gearing is combined with this shaft to transmit motion to the hour-hand shaft. The hour-hand shaft I have not shown, as it has nothing to do with my invention. Every time an electric circuit is completed through the electro-magnet A^{12} , the latter will shift its armature A^{13} and cause an electric current to flow from the battery D to the electro-magnet e^4 . The latter will thus be energized and will vibrate the lever e^2 . The 15 pawls of the lever e^2 will then move the wheel e' and shaft e the distance of one tooth on said wheel. This will occur once every minute. The minute-hand will be moved in this way once every minute for the distance of a minute 20 over the dial of the clock.

I will now describe the manner in which the electric current flows to each electro magnet e^4 . One end of the wire of the electro-magnet e^4 is connected with the line-wire C^2 , and the 25 other end of the wire of such electro-magnets is connected to the line-wire C^3 . Each time the sweep second-shaft A in its rotation permits the swinging arm A^3 and the rod A^5 to make contact, and the electro-magnet A^{12} is, 30 in consequence thereof, energized so as to shift its armature against the contact-piece a^5 , and an electric current flows from the battery D over the line-wires C^2 C^3 , the electro-magnets e^4 of the electric or secondary clocks will be 35 energized. The pawl-levers e^2 will then be vibrated and will rotate the wheels e' one tooth, causing the shafts e to carry the minute-hands over the dials a distance sufficient to indicate one minute upon the dials. Each electric or 40 secondary clock is provided with a tubular shaft, e^{12} , fitting upon the shaft e and provided with a wheel, e^{13} , having thirty-one teeth. Combined with this wheel e^{13} is a pawl-lever, e^{14} . On the pawl-lever e^{14} the armature e^{15} of 45 an electro-magnet, e^{16} , is mounted. One end of the wire of the electro-magnet e^{16} is connected to the line-wire C^2 , and the other end thereof is connected to the line-wire C^3 . Each time the rotation of the shaft B^{11} of the primary 50 clock or regulator effects a contact of the swinging arm B^6 with the rod B^5 , which will be once every day, the electro-magnet B will be energized so as to shift its armature B^2 over against the contact-piece b^5 , whereupon an electric 55 current will be caused to pass from the battery D over the line-wires C^2 C^3 . Then the electro-magnets e^{16} of these electric or secondary

clocks will be energized, so as to attract their armatures e^{15} and vibrate the pawl-levers e^{14} . Wheels e^{13} will thus be moved one tooth. Calendar-hands on the shafts e^{12} will then be moved over the dial sufficiently far to point to the date of another day. Obviously the primary clock or regulator must be so organized that the swinging arm A^3 cannot make contact with the rod A^5 at the same time that the swinging arm B^6 makes contact with the rod B^5 . Springs e^{17} retract the pawl-levers e^2 e^{14} of the electric or secondary clocks after they are severally retracted by the electro-magnets e^4 so 75 e^{16} . Stops e^{18} , consisting, preferably, of adjustable screws, are employed to limit the movements of the pawl levers.

I will now describe means whereby the electric or secondary clocks may be set from the 85 office where the primary clock is located. G' G^2 designate keys consisting, severally, of a metal frame, g , and a metal lever, g' , journaled to the frame g and capable of being rocked up and down. The lever g' is provided on its under side with a contact-piece. The frame g is provided beneath the lever with a contact-piece, g^2 , which is insulated from the frame. A wire, G^3 , extends from the rod B^5 of the primary clock or regulator, and is connected to the levers g' of the keys G' G^2 . A wire, G^4 , extends from the binding-post in which the wire B^4 is secured to the contact-piece g^2 of the key G' , and a wire, G^5 , extends from the binding-post A^{11} , in which the wire A^{10} is secured, to the contact-piece g^2 of the key G^2 . By depressing the lever g' of the key G' a communication with the battery A^8 will be made from one pole along the wire A^7 to the wire B^9 , from the latter to the wire G^3 , thence 90 to the frame g' of the key G^2 , thence to the lever of the key, thence to the contact-piece g^2 of the key, and along the wire G^4 to the wire of the electro-magnet B. As the other pole of the battery is always in communication with the wire of the electro-magnet, the circuit is then complete. Each time the key G' is thus 95 operated the armature B^2 will be shifted over to the contact-piece b^5 , whereby an electric current from the battery D will energize the electro-magnets e^{16} of the secondary or electric 100 clocks, so as to cause the latter to shift the pawl-levers e^{14} and through them the wheels e^{13} and calendar-hands. In this way the calendar-hands of the electric or secondary clocks 105 may be set. By depressing the lever g' of the key G^2 a communication with the battery A^8 will be made from one pole along the wire A^7 to the wire B^9 , thence to the wire G^3 to the frame g of the key, thence to the lever g' of the key, thence to the contact-piece g^2 of the key, from the latter along the wire G^4 to one 110 end of the wire of the electro-magnet A^{12} . The other end of the wire of the electro-magnet A^{12} being in communication with the battery A^8 through the wire A^9 the circuit is 115 complete. Whenever the key G^2 is thus operated, the electro magnet A^{12} will shift its armature A^{13} over against the contact-piece 120

a^5 , and a current of electricity will pass from the battery D over the line-wires C' C² to the electro-magnet e⁴ of the electric or secondary clocks. Then the electro-magnets e⁴ will operate the pawl-levers e² and cause the latter to shift the wheels e' of the shafts e, carrying the minute-hands. Obviously galvanometers V may be combined with the line-wires C' C² C³ in the office to indicate their electrical conditions.

I will now describe means whereby the electro-motive force will be sustained at points distant from the office where the battery D is located. I designate a supplemental battery connected at one pole by a wire, I', with the line-wire C³, and at the other pole by a wire, I², and branch wires with the armatures J⁵ J⁶ of two electro-magnets, J' J². The wire of the electro-magnet J' is connected at one end with the line-wire C² and at the other end with the line-wire C³. The armature J⁵ is swung in one direction by the attractive force of the electro-magnet J' and retracted by a spring, j. When attracted by the electro-magnet, it is moved over against a contact-piece, i⁵, which is electrically connected with the line-wire C². When retracted by the spring j, it is moved over against a contact-piece, i⁴. The wire of the electro-magnet J² is connected electrically at one end with the line-wire C³ and at the other end with the line-wire C'. When it attracts its armature J⁶, the latter is moved over against a contact-piece, i⁶, which is electrically connected with the line-wire C'. When retracted, it is moved over against a contact-piece, I⁶. When the electric current is caused to pass from the battery D over the line-wires C' C³, the electro-magnet J² will be energized so as to attract its armature J⁶, whereupon a current of electricity will flow from the battery I over the line-wire I², armature J⁶, and contact-piece i⁶ to the line-wire C', and from the line-wire C³ back along the wire I' to the battery I'. Whenever a current of electricity is caused to flow from the battery D over the line-wires C² C³, the electro-magnet J' will be energized, so as to shift its armature J⁵ over against the contact-piece i⁵, whereupon the current of electricity will flow from the battery I over the wire I², armature J⁵, and contact-piece i⁵ to the line-wire C², and back again from the line-wire C³ to the battery. It will be seen that the battery I will always be automatically connected with the line-wires in such manner that its electric current will supplement the electric current traversing the line-wires from the main battery D. There may, of course, be any desirable number of supplemental batteries I combined with appendages such as I have described in conjunction with the supplemental battery I which I have illustrated.

I do not here claim the features of the primary clock or regulator, or the features of electric or secondary clocks shown and described in this application, except in combi-

nation with other things, as hereinafter particularly specified.

I intend to file applications for Letters Patent covering the novel features of my primary clock or regulator and the electric or secondary clocks.

I have filed on June 18, 1886, an application for patent, numbered 205,562, for an improvement in primary clocks for electric time-indicating systems, in which I claim special features of construction in said primary clock. I do not herein lay claim to the special construction of said clocks as they are claimed in said application.

I have also filed an application for patent, numbered 205,849, for an improvement in electric or secondary clocks, June 18, 1886, in which I claim special features of construction of a secondary clock. I do not herein lay claim to the special construction of said clocks as they are claimed in said application.

I have filed an application for Letters Patent for an improvement in electric time-indicating systems, numbered 201,400, May 6, 1886. In that application I show a primary clock, line-wires leading from said clock to electro-magnetic mechanism for reversing the direction of the current, a battery for supplying electricity to said line-wires, other line-wires leading from said reversing mechanism to secondary clocks, an electro-magnet in circuit with the wires leading from the reversing device for operating the hour and minute hands, and another electro-magnet in circuit with the electro-magnets in the secondary clock and also with the line-wires leading thereto a circuit-changing device, whereby when the current is reversed by the reversing mechanism the electro-magnets in the secondary clock will be alternately magnetized: In said application I also show a supplemental battery, an electro-magnetic mechanism operated by the main battery to connect the supplemental battery with the line-wires in a manner to supply a current of electricity in the same direction as the main battery. In said application I also show hand-keys and connections in circuit with the secondary clocks and the primary clock for setting the secondary clock. I do not in the present application lay claim, broadly, to the electric time-indicating system therein claimed.

I have also filed an application for Letters Patent for an improvement in electric time-indicating systems, numbered 206,464, dated June 18, 1886. In that application I show a regulator or mechanical clock in circuit with secondary or electric clocks, said secondary or electric clocks being each connected with a battery to said circuit. In that application I also show the secondary or electric clock connected each with a battery in multiple arc to said circuit. In that application I also show a local circuit connected with

contact-pieces in the regulator, and a main circuit composed of a number of sections having secondary or electric clocks, batteries in circuit in each of the sections, those sections from which other sections extend having electro-magnetic closers for the said sections, which extend therefrom, and the local circuit which is connected with the contact-pieces in the regulator, having electro-magnetic circuit-closing mechanism for the section or sections of the main circuit extending from the place where the regulator is located. I do not in the present application lay claim, broadly, to the electric time-indicating system therein claimed.

What I claim as my invention, and desire to secure by Letters Patent, is—

1. In an electric time-indicating system, the combination of a primary clock or regulator having two circuit-closing mechanisms, line-wires adapted to form two circuits, and electric or secondary clocks severally having two electro-magnetic mechanisms for operating different parts, substantially as specified.
2. In an electric time-indicating system, the combination of a primary clock or regulator having two circuit-closing mechanisms, line-

wires adapted to form two circuits, electro-magnets having their armatures connected with certain of the line-wires, a main battery for supplying electricity to the line-wires and connected at one pole with contact-pieces, against which the said armatures will be vibrated when the said electro-magnets are energized, and connected at the other pole to one of the line-wires which is not connected with the armatures, and local-circuit wires connected to the coils or wires of the electro-magnets and extending to circuit-closing mechanism in the primary clock or regulator, substantially as specified.

3. In an electric time-indicating system, the combination of a primary clock or regulator having two circuit mechanisms, line-wires adapted to form two circuits, a main battery, a supplemental battery, and electro-magnetic mechanism for connecting the supplemental battery with either of the two circuits, as circumstances may require, substantially as specified.

C. A. HUSSEY.
